UNITED STATES PATENT OFFICE.

WILLIAM SIEVERS, OF ST. LOUIS, MISSOURI.

DESIGN FOR AN AUTOMOBILE-TIRE LOCK.

54,336.

Specification for Design.

Patented Dec. 23, 1919.

Application filed August 29, 1919. Serial No. 320,747. Term of patent 14 years.

To all whom it may concern:

Be it known that I, WILLIAM SIEVERS, a citizen of the United States of America, residing at St. Louis, in the State of Missouri, have invented a new, original, and ornamental Design for Automobile-Tire Locks, of which the following is a specification, reference being had to the accompanying drawing, forming a part thereof.

The drawing is a front elevation of an automobile tire lock showing my new design.

I claim:

The ornamental design for an automobile tire lock substantially as shown.

In testimony that I claim the foregoing I hereunto affix my signature.

WILLIAM SIEVERS.
